US00D472631S

(12) **United States Design Patent** (10) Patent No.: **US D472,631 S**
Kirsch et al. (45) Date of Patent: ** Apr. 1, 2003

(54) **CLIP**

(75) Inventors: **Wolff M. Kirsch**, Redlands, CA (US);
Douglas J. Cuny, Bethel, CT (US);
Roberto Pedros, Seymour, CT (US);
Yong Hua Zhu, Redlands, CA (US)

(73) Assignees: **Tyco Healthcare Group LP**, Norwalk,
CT (US); **Spinnaker R&D Associates**,
Englewood, CO (US)

(**) Term: **14 Years**

(21) Appl. No.: **29/139,771**

(22) Filed: **Apr. 5, 2001**

(51) LOC (7) Cl. **24-02**

(52) U.S. Cl. **D24/143**

(58) Field of Search D24/143; D8/72,
D8/390, 394, 393, 392, 391, 395, 396;
606/151, 157, 158, 143, 142, 198; 227/902

FOREIGN PATENT DOCUMENTS

EP	285776 A	10/1988
FR	2626772	8/1989

Primary Examiner—Ian Simmons

(57) **CLAIM**

We claim the ornamental design for a clip, as shown.

DESCRIPTION

FIG. 1 depicts a perspective view of a clip.

FIG. 2 depicts a right side view of a clip.

FIG. 3 depicts a left side view of a clip.

FIG. 4 depicts front view of a clip.

FIG. 5 depicts a rear view of a clip.

FIG. 6 depicts a top view of a clip; and,

FIG. 7 depicts a bottom view of a clip.

1 Claim, 3 Drawing Sheets
